UNITED STATES PATENT OFFICE.

HARRY J. SMITH, OF NEW YORK, N. Y.

APPARATUS FOR MAKING ICE.

1,299,800.

Specification of Letters Patent.

Patented Apr. 8, 1919.

Application filed March 15, 1918. Serial No. 222,574.

To all whom it may concern:

Be it known that I, HARRY J. SMITH, a citizen of the United States, and a resident of the borough of Bronx, county of Bronx, 5 city and State of New York, have invented certain new and useful Improvements in Apparatus for Making Ice, of which the following is a specification.

My improvements relate to ice making apparatus set forth in Letters Patent No. 10 1,270,455, issued to me June 25, 1918, and are designed to still further simplify and cheapen the manufacture of "plate" ice,—the distinctive features of my present invention being the making of the divisional members between the coil partitions of inverted wedge shape rigidly secured in position, and in the use in connection therewith of stirrup straps for facilitating the removal 15 of the wedge shaped cakes of ice formed between said coil partitions and the said divisional members, all as hereinafter fully set forth.

In the accompanying drawings, 20 Figure 1, is a diagrammatic view indicating in plan a portion of an ice tank having compartments constructed in accordance with my invention;

Fig. 2, is a sectional elevation of portions 25 of one of the coil-partitions;

Fig. 3, is a transverse section taken upon plane of line 3—3, Fig. 2;

Fig. 4, is a sectional elevation showing in outline one of the ice block pockets;

Fig. 5, is a perspective of one of the ice 30 blocks as removed from a pocket or matrix;

Fig. 6, is a top view of one of the divisional members;

Fig. 7, is a flat side elevation of one of the 40 divisional members partly broken away and in section;

Fig. 8, is an end view of one of the divisional members, partly in section;

Fig. 9, is a transverse section taken upon 45 plane of line 9—9, Fig. 7;

Fig. 10, is a sectional detail upon an enlarged scale showing the air blast control;

Fig. 11, is a sectional detail of the upper 50 part of one of the coil-partitions with one of the divisional members connected therewith, both partitions being broken away;

Fig. 12, is a detail of a coupling plate by which the divisional members may be secured at top to the coil-partitions.

55 The tank T, may be of any desired size,

construction or dimensions, and needs no special description, its requirements and functions being well known in the art. It is formed into a series of elongated compartments by means of the partitions P, which 60 house the ammonia coils A, in a manner also well known in the art.

The coil partitions P, extend to the floor of the tank and entirely across the same, and are formed with metallic side face plates p, 65 p, which contact directly with the ammonia coil A. The upper portion or head p', of each coil-partition P, may be formed of wood, with a longitudinal recess p³, for the accommodation of the air blast pipe b, which 70 extends practically from one end of the coil-partition P, to the other and is provided with a valve b', and connected with a suitable source of compressed air supply. This air pressure pipe b, is formed with a series 75 of nipples b², b², which protrude laterally through the head p', of the coil-partition P, to which nipples rubber tubes may be attached.

The coil-partitions P, are arranged parallel to each other in the tank and a distance apart equal to the thickness of the ice block desired, say twelve inches or so. That is to say the width of the longitudinal compartments prescribes the thickness of the 80 ice blocks to be produced. The length of the ice blocks is prescribed by the spacing apart of the divisional members D, D, which subdivide the longitudinal compartments into a series of matrices or pockets c, c, extending 85 from the tops of the coil-partitions P, to the bottom of the tank.

The width of these divisional members D, 90 is equal to the distance between the opposed side face plates p, p, of adjoining coil-partitions P, so that the longitudinal edges d, d, of said divisional members D, fit snugly between and contact closely with said opposed side face plates p, p, of the said coil-partitions P, when the divisional members 95 are positioned and arranged between the latter, as indicated for instance in Fig. 1. Hence, the divisional members, being metallic, and good conductors of heat, bridge over the space between the opposed face plates 100 p, p, and connect them contactually in such manner as to act effectually as auxiliary freezing plates by which the heat is abstracted from the water in the pockets c, 105 and transmitted to said side face plates p, p, 110

of the coil-partitions P, to be eliminated by the refrigerative action of the ammonia coil in the usual manner.

In the present case the divisional members D, are secured permanently in positions by any suitable means, as may be found most expedient in practice. In the drawings I have shown them as connected at top to the coil-partitions P, by means of coupling 10 plates d^x, and their lower portions should also be firmly held in place in the tank by suitable means. By reference more particularly to Figs. 4, 6 and 8, it will be seen that the main novelty in my present structure 15 consists in making the broad flat side walls of my divisional members convergent upward,—the base d⁴, being larger than the top d⁵, so that each divisional member D, in cross section is essentially an inverted 20 wedge-shaped end partition for adjoining ice pockets or compartments c. This is illustrated diagrammatically in Fig. 4, while Fig. 5, shows the resultant wedge-shape cake of ice produced in each pocket by the freezing process,—h, being a U-shaped strap or 25 stirrup of relatively thin sheet metal one of which is placed in each pocket c, preparatory to freezing the water therein. The straps h, formed with end eyelets h', afford 30 convenient means for raising and manipulating the ice blocks intact, from which they may be readily stripped when desired, as their hold on the ice is only superficial.

The metallic head d', of each divisional member D, forms the support for a steam pipe s, and for an air blast pipe b³, which extends down to a discharge orifice b⁴, positioned at or near the lower edge of the divisional member and on one side thereof. 35 The lower end of the blast pipe b³, is of course sealed except for the discharge orifice b⁴, which is the only means provided for the escape of air from said tube b.

The steam pipe s, does not extend to the 40 bottom of the divisional member D, so that steam introduced into the latter through it may circulate therein freely; and the head d', is formed with exhaust openings d³, d³, for the relief of internal pressure. The 45 water of condensation may be removed from the divisional members by suction hose lowered to the bottom thereof when necessary through any one of the said exhaust openings d³, d³.

The steam pipe s, may be connected with 50 a suitable source of steam supply by a flexible hose s', or equivalent means; and a flexible hose b⁵, or the equivalent thereof may connect the upper end of the blast pipe b³, with 55 one of the protuberant nipples b², of the air pressure pipe b. These steam and air connections in my present arrangement may be permanent since the divisional members are 60 fixed, and this represents a considerable saving 65 in manipulation and time as compared

with the use of the removable divisional members described in my aforesaid concurrent application No. 150,912.

Interposed between the air supply pipe b⁵, and the air blast pipe b³, is an anti-clogging 70 air pressure device e, consisting of a plug formed with a relatively small inlet port e', as compared with the cross areas of the supply pipe b⁵ and of the blast pipe b³. Thus, supposing the air to be delivered by 75 the supply pipe at an initial pressure say of fifteen pounds, the bore of the inlet passage e', may be so small as to reduce the pressure in the blast pipe b³, to two or three pounds in excess of atmospheric pressure, which is 80 sufficient to effect the requisite agitation of the water to insure clear ice. Supposing however that the ice congeals over the discharge orifice b⁴, so as to impede or stop the outflow of air from the blast pipe b³, it is 85 obvious that the pressure in said blast pipe b³, will gradually increase until the initial pressure is reached, or until the increase of pressure is sufficient to overcome the obstruction, and the initial pressure provided is 90 calculated to overcome any possible obstruction of this sort. As a result the blast pipe b³, automatically clears its discharge orifice b⁴, of any obstruction by congelation, and a steady uniform and effective injection into 95 the water of air under pressure is insured.

The ice blocks after being frozen solid, are loosened up superficially in the usual way by heat introduced into the coils A, and by steam introduced into the divisional members D, so as to facilitate the withdrawal of the ice blocks from their pockets c, by means of the straps h.

It is a well known fact in the art that two 100 "plates" of ice cannot be frozen together effectively; that they will soon separate along the plane of juncture. Hence it is 105 not the mere placing of the coil-partitions in closer relationship that enables me to produce homogeneous blocks of "plate" ice, 110 but the use of the divisional members D, bridging over and extending from one coil-partition to the other, whereby the block is formed and built up gradually from all four sides, as I have attempted to illustrate by 115 dotting in Fig. 1. By this means I practically attain blocks of pure, clear, hard, homogeneous and dense ice of any desired size and dimensions having all the qualities of first class "plate" ice, so called, without any of 120 the disadvantages or waste heretofore involved in the manufacture of blocks of plate ice, since my blocks require no trimming or 125 truing up. In fact, in this respect I attain all the advantages of "can" ice, while the product is superior thereto for reasons heretofore stated. And ice blocks produced by my method and apparatus are not only 130 superior to "can" ice, but they are cheaper, and it is feasible to make them of any de-

sired size and weight, whereas can ice is limited practically to the production of three hundred pound cakes. Furthermore the manufacture of can ice involves large floor space and the manipulation of many parts, whereas my apparatus is compact and requires only the minimum of floor space and equipment. And from the fact that the block is frozen solid from all four sides of the mold, it can be produced in much less time than either "can" ice or blocks formed from plate ice as heretofore.

By providing for the agitation of the water by air ejected directly from the sides of the divisional members I obviate the use of air pipes plunged bodily as heretofore into the body of water to be frozen; and by my air pressure accumulating device I guard against interruption or stoppage of such water agitation by air blast.

By the provision of my fixed inverted wedge shaped divisional members D, and the manipulating stirrups h, I so facilitate the "harvesting" of the ice as to save one third of the time and labor involved in the operation as compared with lifting out, temporary storage, and replacement of the removable divisional members described in my aforesaid concurrent application No. 150,912, and with less waste of, and damage to, the

ice. Not only are the ice blocks more easily handled, but the steam or air pipe connections are not disturbed, and there is less wear and tear to the parts generally.

What I claim as my invention and desire to secure by Letters Patent is,

In ice forming apparatus of the character designated, the combination of a tank, a plurality of coil-partitions arranged in parallelism therein, and fixed hollow metallic divisional members, interposed between and contacting directly with the opposed metallic sides of adjacent coil-partitions, each of said metallic division members being of inverted wedge shape in cross section, and being formed with an air pressure pipe extending to the bottom thereof and opening through the side thereof, and with a steam injection pipe extending to the lower portion thereof, together with U-shaped stirrup straps positioned in the ice compartments between adjacent divisional members and coil-partitions whereby the wedge shaped blocks of ice formed in said ice compartments may be removed intact, for the purpose described.
